UNITED STATES PATENT OFFICE.

WARWICK JAMES LEWIS, HERBERT PEARCE, AND CHARLES HOLLIWELL,
OF MANCHESTER, ENGLAND, ASSIGNORS TO THE MERGENTHALER LINOTYPE COMPANY, OF NEW YORK, N. Y.

JUSTIFYING MECHANISM FOR LINOTYPE-MACHINES.

SPECIFICATION forming part of Letters Patent No. 614,561, dated November 22, 1898.

Application filed March 17, 1898. Serial No. 674,230. (No model.)

To all whom it may concern:

Be it known that we, WARWICK JAMES LEWIS, HERBERT PEARCE, and CHARLES HOLLIWELL, residing at Manchester, in the county of Lancaster, England, have invented certain new and useful Improvements in and Connected with the Justifying Mechanism of Linotype-Machines; and we do hereby declare the following to be a full, clear, and exact description of the invention, such as will enable others skilled in the art to which it appertains to make and use the same.

The present invention relates to improvements in and connected with the justifying mechanism of linotype-machines. It is especially applicable to the justifying mechanism of the well-known Mergenthaler linotype-machine, and for that reason its application to it has been selected for illustration and detailed specification. Further information as to the general construction and operation of the said machine is to be found in the specification of Letters Patent of Great Britain dated September 16, 1890, and in United States Letters Patent of the same date, Nos. 436,531 and 436,532.

Referring to the accompanying drawings, Figure 1 is a front elevation of the transporter and as much of the adjacent portion of the machine as concerns the present invention. Fig. 2 is a sectional side elevation from the left side of the machine.

In the Mergenthaler linotype-machine independent or individual matrices Y, each being a rectangular plate of metal, and space-bars, each being a double wedge, are composed into a line by suitable mechanism and transferred to a moving part of the machine, which part is hereinafter referred to as the "transporter" N, commonly known in the United States as the "first elevator" or "yoke." This transporter consists of a vertical bar or frame, from the top of which project a pair of parallel horizontal rails N' N². The matrices hang from and between the latter by their top shoulders y' y', which engage in grooves in the respective rails N' N², the space-bars hanging by their shoulders z² z². The transporter N has a reciprocating verti-

cal motion between suitable guides N³ N³. 50 These guides are fixed to the lower part of the vise-frame P' and to the abutment P, which forms the top of it. This vise-frame P' and abutment P with it are held up to the main frame of the machine in the position 55 illustrated by vise-screws p²⁵ p²⁵. At the moment when the delivery of the composed line of matrices and space-bars into the transporter N has been completed the latter stands in the position illustrated by the full lines in 60 Fig. 1 and the dotted lines in Fig. 2. It is then moved downward into the position illustrated by the full lines of Fig. 2, so as to present the said line to the casting mechanism. The only parts of that mechanism included 65 in the drawings are the mold-wheel O, its bearing o³, and the mold-block o¹¹ for the body of the linotype. After the linotype has been cast in the mold-cavity and into and against the line of matrices the transporter N is moved 70 vertically upward to a level higher than that at which it received the composed line to meet the distributing mechanism. The latter is not included in the drawings, because it is not affected by the present invention. 75

The transporter N is acted on throughout all its motions, as well as while it is standing still, by a cam-and-lever mechanism or by equivalent cam-and-spring devices. In addition to the top shoulders y', projecting from 80 the top corners of each matrix Y, there are two corresponding shoulders (marked y' in Fig. 2) projecting from the bottom corners. When the transporter N is standing in the casting position in front of the mold-wheel 85 O, (the one illustrated by the full lines in Fig. 2,) all the rear bottom shoulders y'—that is, those next to the mold-block o¹¹—stand under the horizontal shoulder or ridge o¹²⁸ on the front of the mold, as shown in Fig. 2. 90

The justification of the composed line—that is to say, its elongation to the precise length required—is effected by thickening each of the space-bars hanging therein. Each of these space-bars consists of a short wedge 95 carrying the pair of shoulders z² z² and a long one z'. The two wedges are tapered in opposite directions and have their tapered sides

loosely dovetailed together. The long wedges z' project for some distance below the composed line in the path of a justifying-plate p^6 . This plate is pushed vertically upward by 5 suitable means, and as the short wedges are held against upward motion by the engagement of their shoulders $z^2 z^2$ in grooves in the rails $N' N^2$ its rise pushes the long wedges z' over the short wedges up through the composed line, thereby thickening each space-bar and elongating the composed line. Fig. 2 shows that the wedges z' have been pushed up. During that elongation the matrices Y are pushed laterally, their bottom shoulders y' 10 rubbing over the rails $N' N^2$ and beneath the ridge o^{128} ; but as the means—cam or spring, as the case may be—by which the transporter N is raised is exerting its full pushing power in an upward direction during the time that 15 the said transporter N is holding the composed line in the casting position and pulling the matrices upward by their top shoulders y' the top front shoulders y' of the matrices Y bear against the front rail N' and the bottom rear ones against the ridge o^{128} . 20

The strong lifting action of the transporter or yoke N causes a severe friction of the upper matrix-shoulders within the yoke and of the lower matrix-shoulders against the under 25 surface of the shoulder on the mold, so that the lateral movement of the matrices is strongly resisted. This resistance in turn causes strong friction against the sides of the justifying-wedges as they are raised through 30 the line. When justification occurs, the friction on the matrix-shoulders and on the justifying-wedges must be overcome. Experience has shown that when the matrix-lines are long and contain a large number of 35 matrices the friction is sometimes so great as to interfere with the justifying action unless an excessive and objectionable upward pressure is applied by the lifting-plate p^6 . The object of the present invention is to reduce the friction on the matrices and spaces during justification by holding down the transporter or matrix-support N , so as to relieve the upper and lower shoulders of the matrices for the time being of pressure and friction. That object is attained by the following means: 40

n^{64} is a catch hanging downward from the top of the transporter N , to which it is pivoted, and with its nose pointing to the rear.

n^{65} is a spring adapted to keep the catch n^{64} 45 pushed to the rear and to permit of its being pushed as far to the front as the present invention requires.

The means by which the transporter N is moved up and down is for the purpose of the 50 present invention adapted to move the transporter a little lower than is absolutely necessary to enable it to present the composed line properly to the casting mechanism—that is to say, a little lower than the bottom of the downward motion before described. As soon as it 55 has been so moved a little lower the spring n^{65} makes the catch n^{64} engage under a fixed

stop n^{66} . Consequently the matrices are practically hanging free from the rails $N' N^2$ and clear of the ridge o^{128} when the wedges $z' z'$ are 70 started upward between them. The bottom edge of the abutment P is utilized as the stop n^{66} , above mentioned.

The invention includes a disengager for disengaging the transporter N at the moment 75 when it must start upward toward the distributing mechanism.

The justifying-plate p^6 above mentioned is worked by two levers. Part of the front end of one of them, p^{12} , appears in Fig. 2. The 80 function of that part is to work the screw p^3 of the vise that holds the composed line cramped lengthwise during the act of casting. The connection between the vise-screw p^3 and the said part of the lever p^{12} consists of a fork 85 p^{26} , virtually fast to the screw p^3 and projecting from it to the rear, a rod p^{51} , pivotally connected by its top end to the said fork and having its bottom end expanded into a loop p^{52} , which receives a lateral extension p^{53} of the 90 lever p^{12} , and a returning-spring p^{54} , surrounding the rod p^{51} and pulling on the top of the loop p^{52} from a bracket p^{55} , fast on the main frame of the machine. The last motion of the lever p^{12} is downward from the position illustrated in Fig. 2, and it consequently pulls the 95 rod p^{51} against the spring p^{54} through a certain arc. The combination of the parts p^{12} , p^{51} , p^{54} , and p^{26} just described is as heretofore. It appears in the specification because the present invention utilizes the downward motion of the fork p^{26} to actuate the disengager. 100

The disengager which we prefer is as follows: n^{67} is a finger practically fast to the end of the rod p^3 and projecting to the front. n^{68} is 105 a horizontal rod turning in bearings $n^{69} n^{69}$, fast on the front face of the abutment P . It has the disengaging-finger n^{70} fast on its opposite end. n^{71} is a finger fast to the rod n^{68} and projecting to the rear. It stands over the 110 finger n^{67} . The respective positions of the fork p^{26} and the fingers n^{67} , n^{70} , and n^{71} are as follows: When the fork p^{26} is at rest, the finger n^{71} rests upon the finger n^{67} and the disengaging-finger n^{70} stands up just behind 115 the catch n^{64} when the latter is engaged with the stop n^{66} . The disengager is held in that position by a spring n^{72} , pulling, preferably, on the finger n^{71} from a fixed point on the main frame of the machine. The action of 120 it is as follows: The above-described pull on the fork p^{26} rocks the finger n^{71} up and the finger n^{70} forward far enough to disengage the catch n^{64} from the stop n^{66} , as indicated by the respective dotted lines in Fig. 125 2, whereupon the transporter N is moved upward. As soon as the justifying-lever above mentioned has completed its downward motion the spring p^{54} returns the fork p^{26} to its normal position, as heretofore, thereby 130 rocking the finger n^{67} downward and leaving the fingers n^{70} and n^{71} to be pulled by the spring n^{72} into the positions illustrated by the respective full lines. The foregoing descrip-

tion of the action of the disengager implies the respective dimensions of the catch n^{64} and the fingers $n^{70} n^{71} n^{72}$.

It will be perceived that the present invention has reference solely to machines in which matrices having shoulders at their upper and lower ends are subjected to pressure and friction on these shoulders during the action of the justifying-wedges. A clear distinction is to be drawn between a machine of this class, in which the lifting action of the matrix-support causes the friction on the matrix-ears, and the machine shown in the Mergenthaler United States Patent No. 425,140, in which the matrices are provided with shoulders at one end only and in which the elevator is locked down for an entirely different purpose and with an entirely different effect from that claimed herein. In the patent referred to the matrices have shoulders at the upper ends only. They do not engage under the mold. They are alined by their upper instead of their lower shoulders, and the yoke is locked down, as stated in the patent, so that it "forces the matrices down to their place with a pressure which is strong," &c., the effect being to increase rather than lessen the friction on the matrix-shoulders during justification.

30 What we claim as our invention is—

1. In a linotype-machine, the combination of a mold, a matrix transporter or support, matrices having upper shoulders to engage said support and also shoulders to engage the mold, justifying-wedges, and means for locking the support down, to relieve the matrices from friction during justification.

2. As an improvement in Mergenthaler linotype-machines, and in combination with the mold, the matrices shouldered at both ends, justifying-wedges and a matrix-support operating as usual, and means for locking the support down during justification, to relieve the matrices and spacers from friction.

3. In a linotype-machine, the combination of the mold, the transporter or carrier N, matrices shouldered to engage the mold and the transporter, justifying-wedges, means tending to lift the transporter, and means for locking the transporter down momentarily during the rise of the justifying-wedges.

4. In a Mergenthaler linotype-machine and in combination with the mold, the transporter, and the shouldered matrices, an automatic latch to lock the transporter down, and means substantially as described for releasing the latch.

5. In a linotype-machine, the vertically-moving matrix support or transporter, N, a spring-actuated catch n^{64} to lock the same down, and a rock-shaft n^{88} , provided at one end with an arm to disengage the catch and arranged at the opposite end to receive motion from a moving part of the machine.

In testimony that we claim the foregoing as our invention we have signed our names in presence of two subscribing witnesses.
